Horatio Atkin
Letters Patent.

The above is referred to in these Letters Patent, and making part of the same, according to my description in the words of the said Horatio Atkin, himself, of his improvement in Cloth and hair Brushes.

The handle of hair is wound between wires, making a spiral brush, and hammered to a suitable length. The spiral brush is then bent into any required shape; and the two ends of the wire, are brought together, and put into a handle, and then secured. Or the two ends of the hair ends, of the wire may be swelled into iron bars, which has a shank, that enters into, and is fastened into the handle. Another method, is, by taking 11, or 12 spiral brushes, placed parallel, at a suitable distance apart.

The ends are then riveted onto iron bars, one at each end; one of the bars having a shank which is fastened into the handle, as before mentioned.

What I claim as my invention is, the construction of the above described Brushes for clothes and hair; but I do not claim the principle of twisting hair, or bristles between wires, for making Brush as thus having been done before. For a further illustration of my invention, I refer to the model and drawing of the same, deposited in the Patent Office. In testimony that the above is a true specification of my invention, I have subscribed my name, before two witnesses, and made oath to the same, at the City of Washington this 19th day of May, 1830.
